C. W. CAVANAUGH,
BABY SWING,
APPLICATION FILED SEPT. 16, 1919.

1,379,082.

Patented May 24, 1921.

INVENTOR:

By Clarence W. Cavanaugh,
Joseph T. T. Bragman, ATTY.

UNITED STATES PATENT OFFICE.

CLARENCE W. CAVANAUGH, OF GLOUCESTER, MASSACHUSETTS.

BABY-SWING.

1,379,082.

Specification of Letters Patent. Patented May 24, 1921.

Application filed September 16, 1919. Serial No. 324,204.

To all whom it may concern:

Be it known that I, CLARENCE W. CAVANAUGH, citizen of the United States, residing at Gloucester, in the county of Essex and State of Massachusetts, have invented 5 certain new and useful Improvements in Baby-Swings, of which the following is a specification.

My invention relates to swings of that 10 class which comprises a safety seat suspended from an overhead support.

Swings of the class referred to are for 15 use by very young babies and therefore should have the seat portion thereof constructed with means for holding the child in such position that the child cannot accidentally fall out. My invention has for its 20 object to provide an improved swing of the class mentioned, and particularly to improve the construction of the seat and of the means for holding the baby in place thereon.

One feature of my improved swing resides in the construction of the seat, which 25 is made with a bottom of strong stiff material such as wood, said seat being provided with three upright walls of canvas or other suitable flexible material secured at their lower edges to said bottom, and said walls 30 consisting of a back wall and two side walls. All three of these walls have their upper portions secured to a rigid frame connected with the means by which the seat is suspended from an overhead support. Another feature of my invention resides in the 35 construction and arrangement of the improved means hereinafter described, for holding the child safely in position upon the seat of the swing.

In the accompanying drawings:

40 Figure 1 is a perspective view of a baby swing constructed in accordance with my invention.

Fig. 2 is a vertical sectional view, on enlarged scale through one side of the seat 45 hereinafter described.

My improved baby swing comprises a 50 portable frame work which includes a rectangular base consisting of four strips of angle iron 1, 2, 3 and 4 fastened at their ends to the lower ends of four upright posts 5. At their upper ends the posts 5 are fastened to a rectangular top frame made up of four marginal strips of angle iron 6, 7, 8 and 9 and a pair of crossed diagonally disposed bars 10 and 11. These bars 10 and 11

are perforated where they cross to receive through them an eye-bolt 12 provided with a nut 13. The eye-bolt 12 has four ropes 14 connected to it which extend downwardly through perforations provided at the ends 60 of a pair of crossed spreader bars 15, and are connected at their lower ends with the seat of the swing.

The seat of the swing comprises a rectangular bottom piece 16 of wood or the 65 like to which are attached the lower ends of three walls 17, 18 and 19, said walls being preferably made from canvas so as to provide yieldable and soft walls for the child to rest against. As herein shown a 70 single piece of canvas is used to make these three walls, the lower marginal portion of said piece of canvas being turned inwardly under the seat 16 as shown in Fig. 2, and secured to the under side of said seat by 75 means of nails 20 and one or more metallic strips 21.

The upper marginal portion of the piece 80 of canvas constituting the walls 17, 18 and 19, is formed with a tubular pocket 23 within which is confined a rectangular metallic frame 24. The lower ends of the ropes 14 are provided with eyes 25 through which the two side bars of this metallic frame 24 extends. 85

The means herein provided for use in securing the child in position upon the seat 16 includes a belt 26 made near its middle with a laterally and downwardly projecting extension 27 fastened by tacks or nails 28, or 90 otherwise, to the front edge of the seat 16.

The middle or body portion of the belt 26 may, as shown, be made up of a piece of canvas to each end of which is fastened one end of a cord or rope 29. The back wall 95 18 has incorporated in it two gromets 30, one near each side of said wall, through which the cords or ropes 29 can be passed.

The child is placed in position upon the seat 16 with its legs at each side of extension 27 and then, with the belt in position across the body of the child, the end ropes 29 are threaded through the gromets 30 to the rear side of back wall 18 where they are tied together. This construction permits of 105 the belt being adjusted nicely to the size of the child, while the middle or body portion of belt 26 being made of a piece of flexible canvas of relatively large area, does not cut into the body of the child to the discomfort 110

and perhaps injury of the latter as is the case with some of the constructions heretofore proposed.

The weight of the child upon the seat 16 causes said seat and the metallic frame 24 to coöperate in holding the side walls flat and taut so as to support the child when it rests or leans against said walls.

What I claim is:

- 10 1. A baby swing having a seat including in its construction a seat bottom; a back wall extending upwardly from said seat bottom formed near each side with an aperture; a belt made near its middle with a laterally and downwardly projecting extension secured near its lower end to said seat bottom near the front thereof, said belt being provided at its ends with flexible terminals, extending through the apertures of the back wall and adapted to be fastened together at the rear of said back wall.
- 15 2. A baby swing having a seat including in its construction a seat bottom; a back wall of canvas or the like extending upwardly from said seat bottom and formed near each side with an aperture; a belt having a middle portion of relatively large area made

from canvas or the like provided at its ends with flexible terminals, said middle portion being made with a laterally and downwardly projecting extension fastened near its lower end to said seat bottom near the front thereof, the end terminals of said belt being adapted to be passed through said apertures and tied together at the rear of 35 said back wall.

3. A baby swing having a seat including in its construction a seat bottom; a back wall of canvas or the like extending upwardly from said seat bottom and formed near each side with an aperture bordered by a gromet; a belt having a middle or intermediate body portion of canvas or the like made near its middle with a lateral extension that is secured near its end to said seat bottom near the front thereof, said intermediate portion being provided at each end with a cord or the like adapted to pass through said gromets and to be tied together at the rear of said back wall.

Signed at Boston, this eleventh day of July, 1919.

CLARENCE W. CAVANAUGH.
